[57] CLAIM

The ornamental design for a heat convection rotating light,
as shown and described.

DESCRIPTION

FIG. 1 is a perspective view of a heat convection rotating light showing my new design;

FIG. 2 is a side elevational view thereof (the opposite side
being a mirror image thereof);

FIG. 3 is a top view thereof;

FIG. 4 is a bottom view thereof; and,

FIG. 5 is a view similar to FIG. 2 except with a cut-out
showing the exterior surface of the suspended interior mem-
ber.
